UNITED STATES PATENT OFFICE.

RALPH V. L. HARTLEY, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

ELECTRIC-WAVE-MODULATING SYSTEM.

Application filed July 7, 1925. Serial No. 41,914.

This invention relates to systems for modulating electric waves and in particular to systems for producing phase modulation.

The art of electric wave modulation, wherein the amplitude of a carrier wave is varied in accordance with the amplitude of a modulating wave, usually a signal wave of some sort, is highly developed and well understood. Likewise the fact that modulation of carrier waves by shifting or varying the frequency thereof in accordance with variations, usually amplitude variations of a modulating wave, is quite generally known. It is further known that, in both of the methods of modulation mentioned above, the resulting modulated waves are of a somewhat complex composition involving several components. One component is a wave of carrier frequency unmodulated, a second is a sideband of frequencies consisting of waves having frequencies represented by the sum of carrier and signal frequencies and a third component is a sideband of difference frequencies. However, in these two methods of modulation the relation which the unmodulated waves of carrier frequency bear to their respective side bands is different. If the side bands in both cases are identical as to phase, the unmodulated carrier wave in the frequency modulated system is in quadrature with the unmodulated carrier wave of the amplitude modulated system.

This invention comprehends a third method of modulation wherein the phase of the carrier wave is modified, and the resulting modulated wave components have phase relations the same as frequency modulated waves and amplitude relations the same as amplitude modulated waves.

An object of this invention is to modulate electric waves by varying their phase in accordance with the variations of modulating waves.

Another object is to produce phase modulated waves and to suppress the unmodulated component of carrier frequency.

A further object is to produce phase modulated waves and to generate other waves, which, by their combination with the phase

modulated wave, enable reproduction of the modulating waves.

An additional object is to transmit signals by varying the phase of carrier waves in accordance with signals and transmitting said modulated waves.

A further object is to produce undistorted phase modulated waves.

A still further object is to maintain secrecy in the transmission of messages by carrier waves.

A feature of the invention is an electromagnetic system for producing phase modulated carrier waves which includes means for producing a rotating field of carrier frequency and means including a vibratory coil controlled by a signal source to cause modulation of the phase of currents induced therein by the rotating field.

Another feature is a means for generating a phase modulated wave including an unmodulated carrier component and in opposition thereto a wave of carrier frequency adapted to suppress the unmodulated component.

A further feature is a means for generating an unmodulated carrier wave of such phase with respect to the sidebands of phase modulated waves that when combined with the phase modulated waves they may be detected to yield the modulating waves.

The invention consists of an arrangement for generating carrier frequency waves and for shifting the phase of these waves so as to cause modulation thereof, includes means for suppressing the unmodulated carrier component of the modulated waves, and means for supplying an unmodulated component of carrier frequency in such phase relation to the sidebands that these latter may be combined in any well known detecting device to yield the signals.

The invention may be practiced by generating a rotating field of carrier frequency and causing this field to traverse a coil which may be vibrated in accordance with modulating waves such as signal waves. Another coil also traversed by the rotating field may be vibrated in opposite phase to generate an unmodulated carrier component

in opposition to that generated in the first coil, whereby this component may be suppressed. Still another coil is provided and so arranged as to have induced in it a wave of carrier frequency of such phase relatively to the sideband components, that the induced wave and sidebands may be combined in any well known detector to yield the modulating wave.

10 In the drawings, a system for modulating the phase of a carrier wave in accordance with signals is illustrated.

The system includes a source of signals including a transformer 10 adapted to have its primary winding connected to a wire line, a microphone speech transmitter or other source of signal waves. A signal translator 20, somewhat similar to a telephone receiver is connected to the transformer 10 and by 15 a system of levers 50 is adapted to produce an angular vibration of coils 30 and 31 of the modulator 32. The modulator is provided with output terminals 33 which may be connected to a wire line, an amplifier, a 20 detector or the like, or to a radio transmitter. 25

The translating device 20 includes a polarized electromagnet 21 including windings 22 upon a permanently magnetized core 23. 30 A diaphragm 24 is positioned in front of the pole faces of magnet 21 and is capable of vibration under the action of received waves. At the center of the diaphragm 24 is attached a T-shaped arm 26 having rods 27 35 pivoted to its free ends. The rods are also pinioned to levers 28 rotatable about axes 29. The levers 28 are pivoted to rods 34 which in turn are pivoted to secondary levers 25. The latter are adapted to actuate 40 rods 35 which are connected at their distant ends to lugs 36 mounted on the coils 30 and 31. The modulator 32 includes pairs of field coils 37 and 38 so positioned that their magnetic fields intersect each other and interlink with the coils 30, 31 and 40. The latter coil is stationary and is positioned coaxially 45 with coils 30 and 31. Field coils 37 are connected in series to a source of carrier waves 41. Field coils 38 are likewise connected in 50 series to a source of carrier waves 42. The waves in sources 41 and 42 have the same frequency but differ in phase by 90° so that in a manner well understood, a rotating field is produced by the coils 37 and 38.

55 The windings of coils 30 and 40 are connected in series to the terminals 33 by means of a switch 43, when in the position shown. When switch 43 engages the contacts 44, the coil 31 which is wound and connected to 60 produce a field which opposes that of coil 30 is included in series with the windings of coils 30 and 40.

Signal waves are transmitted by transformer 10 to windings 22 of magnet 23, and 65 the diaphragm 24 is caused to vibrate in ac-

cordance with the amplitude of the received waves. The movements of the diaphragm 24 are transmitted through the lever arrangement 50 to cause the coils 30 and 31 to be vibrated in opposite directions.

When waves are supplied from sources 41 and 42 to the field coils 37 and 38, and when coils 30 and 31 are stationary, there are induced in coils 30 and 31 carrier waves corresponding to the frequency of the waves 75 from sources 41 and 42. During the vibration of coils 30 and 31 the phase of the induced carrier waves is modulated or varied in a manner more fully explained in a succeeding part of this description. A modulated wave comprising sideband frequency components and an unmodulated component of carrier frequency, somewhat similar to the corresponding waves produced by ordinary amplitude modulation is produced.

80 In the stationary coil 40 an unmodulated carrier wave is generated but since this coil is at a position 90° from the mean position of the coils 30 and 31, the phase of the carrier wave generated therein differs by 90° 85 from the phase of the unmodulated carrier frequency component of the resulting modulated waves produced in coils 30 and 31.

With switch 43 in the position shown, the modulated waves generated in coil 30 and the unmodulated carrier waves generated in coil 40 are impressed upon the terminals 33. These waves may be supplied to an ordinary detector circuit either connected directly to terminals 33 or arranged to receive the modulated waves and the accompanying unmodulated carrier component from coil 40 after they have been transmitted from a radio transmitting system. The manner in which these waves may be detected will be more fully explained later.

If the switch 43 be thrown to contacts 44, there will be added to the waves from coils 30 and 40, the modulated waves from coil 31. Due to the manner in which coils 31 110 and 30 are wound these modulated waves will include an unmodulated carrier frequency component differing in phase by 180° from the corresponding component of waves from coil 30. Accordingly the unmodulated component of carrier frequency is neutralized and there appear at the terminals 33 only the waves of sideband frequencies accompanied by an unmodulated carrier component from the coil 40 which is 90° different from the corresponding unmodulated components generated in coils 30 and 31. These waves may also be combined to effect detection in a manner to be hereinafter described.

If desired the coil 40 may be omitted and a suitable source of carrier waves may be supplied at the receiving station to cause detection of the phase modulated sidebands. Again the waves from coil 40 may also be 130

separately transmitted to the receiving station if desired.

In the arrangement shown in the drawings the frequency of waves from the carrier sources 41 and 42 may be arbitrarily represented by

$$f_0 = \frac{p}{2\pi};$$

10 the waves generated in coil 30 may be represented by the expression:

$$A \cos (pt + \theta)$$

where θ represents the phase angle of the wave induced in the coil 30 as determined by its angular position with respect to the coils 37 and 38, t represents time and A a constant. When the coil 30 is vibrated, the phase angle varies as a function of this vibration and if the vibration is sinusoidal, θ may be represented by the expression $a \cos$

qt for coil 30, for example, and by $-a \cos qt$ for coil 31 where the frequency of vibration is represented by

$$f_s = \frac{q}{2\pi}$$

and a is a factor, expressed in radians, representing the magnitude of the phase angle variations of coil 30 as determined by the angular vibration of the coil. Thus, the wave produced in coil 30 during vibration, that is, the phase modulated wave, may be properly represented by an expression:

$$M = A \cos (pt + a \cos qt) \quad (1)$$

The character of this wave will be better understood by analyzing it into its component frequencies. By a trigonometric transformation, the expression may be written:

$$M = A [\cos pt \cos (a \cos qt) - \sin pt \sin (a \cos qt)] \quad (2)$$

The right-hand cos and sin function, respectively, of each term of equation (2) may be expanded as follows:

$$\cos (a \cos qt) = 1 - \frac{a^2}{2} \cos^2 qt + \frac{a^4}{4} \cos^4 qt - \frac{a^6}{6} \cos^6 qt \dots \quad (3)$$

and

$$\sin (a \cos qt) = a \cos qt - \frac{a^3}{3} \cos^3 qt + \frac{a^5}{5} \cos^5 qt - \frac{a^7}{7} \cos^7 qt \dots \quad (4)$$

By substituting the expressions (3) and (4) in equation (2) we have

$$M = A \left[\cos pt \left(1 - \frac{a^2}{2} \cos^2 qt + \frac{a^4}{4} \cos^4 qt - \frac{a^6}{6} \cos^6 qt \dots \right) \right. \\ \left. \sin pt \left(a \cos qt - \frac{a^3}{3} \cos^3 qt + \frac{a^5}{5} \cos^5 qt - \frac{a^7}{7} \cos^7 qt \dots \right) \right] \quad (5)$$

45 The terms in powers of a are negligible, when a , which represents the amplitude of vibration of coil 30, expressed in radians, is small as compared to unity. After drop-

ping all terms above the first power we have

$$M = A [\cos pt - a \sin pt \cos qt \dots] \quad (6)$$

By a well known trigonometric transformation this equation becomes:

$$M = A \cos pt - \frac{Aa}{2} \sin (p - q) t - \frac{Aa}{2} \sin (p + q) t \quad (7)$$

It is evident that the first term represents unmodulated carrier current. The second and third terms represent a pair of sidebands similar to those resulting from amplitude modulation. For an explanation of this fact see U. S. Patent 1,449,382, issued to J. R. Carson, March 27, 1923.

60 The expression for an amplitude modulated wave may be written in the form:

$$I = A \sin pt + B \sin pt \cos qt + \dots \quad (8)$$

Upon comparing this expression (8) with 65 equation (6), it will be seen that the unmodulated carrier component in equation (6) is

represented by a cos function, whereas in equation (8) it is represented by a sin function. The expressions for the sidebands on the other hand are represented by similar functions in the two equations. The physical significance of this difference is that the unmodulated carrier component, in the case of phase modulated waves represented by equation (6) is 90° different in phase with respect to the sideband components than the corresponding unmodulated carrier component of amplitude modulated waves.

If the voltage wave represented by equation (7) be supplied to a device operating

upon the square law principle, that is, a detector having current relations given by the expression:

$$I_b = a_0 + a_1 V + a_2 V^2 + \dots \quad (9)$$

After expanding this expression we obtain terms including second power terms representing double the carrier frequency and double the sideband frequencies, which

The resulting terms that may yield the signal frequency are the product terms in the squared expression and not the square terms, that is, we have the equation:

$$I_b = a_0 + a_1 V + a_2 A^2 \left(\cos pt - \frac{a}{2} \sin (p+q)t - \frac{a}{2} \sin (p-q)t \right)^2 \quad (10)$$

this expression, by trigonometric transformation yields terms representing signal-frequency components as follows:

$$a_2 A^2 \left(-\frac{a}{2} \sin qt + \frac{a}{2} \sin qt \right) \quad (12)$$

Since the two terms in this expression are equal to each other and opposite in sign, they cancel and hence no signal frequencies are produced by the detection process.

However, if the unmodulated carrier frequency component represented by the term $\cos pt$ of equation (6), should have a phase 90° different, that is, if it should be represented by $\sin pt$, then the signal frequency components resulting from detection would have the same sign and would not cancel but would add and accordingly signal waves would be derived from the detection of the phase modulated waves. The function of coil 40 is to supply an unmodulated carrier frequency wave of the phase necessary for this purpose as already explained.

By a similar development of equation (1) with the sign of the term $a \cos qt$ changed it may be readily shown that in coil 31 a modulated wave is produced in which the sideband components are in phase with the sidebands of coil 30 but in which the unmodulated carrier frequency component is opposite in phase to the corresponding component waves in coil 30.

The invention herein may be used to advantage for secret signaling, since the modulated components produced in either coil 30 or 31 may be transmitted with the unmodulated carrier frequency component, in such phase relation thereto that detection in unauthorized receiving circuits would result in neutralization of the modulating currents, as explained above. However, by supplying locally at an authorized receiving station a carrier frequency wave in the proper phase relation to the modulated components, they may be detected to yield the signals.

Although this invention has been described in connection with a specific embodiment, it is not to be understood as limited

terms may be excluded, since the waves represented thereby are readily separable from the waves of carrier and sideband frequency. Considering the remaining terms; i. e.

$$a_2 A^2 (-a \cos pt \sin (p+q)t - a \cos pt \sin (p-q)t) \quad (11)$$

to this particular embodiment, since numerous modifications thereof may be made by a person skilled in the art without departing from the spirit of applicant's invention, the scope of which is to be determined by the appended claims.

What is claimed is:

1. The method of modulation which comprises generating a high frequency carrier wave, shifting the phase of said wave to produce sideband frequencies and an unmodulated carrier frequency component, generating a second wave of carrier frequency, shifting the phase of said second wave so as to generate sidebands in phase with said first mentioned sidebands and an unmodulated carrier frequency component opposite in phase to said first mentioned component, and combining said waves to cause suppression of said first mentioned unmodulated component.

2. The method of modulation which comprises generating a carrier frequency wave, generating a second wave of the same frequency but differing in phase, causing said waves to produce a rotating magnetic field, generating a carrier frequency wave in accordance with the rotation of said field, and shifting the phase of said last mentioned wave in accordance with signals.

3. The method of modulation which comprises generating a carrier frequency wave, generating a second wave of the same frequency but differing in phase by 90° from said first mentioned wave, producing a rotating magnetic field by the cooperation of said waves, generating a plurality of carrier frequency components in accordance with the rotation of said field, shifting the phase of certain of said components whereby the resultant unmodulated components produced differ in phase from each other.

4. The method of signaling which comprises generating a rotating magnetic field, causing said field to produce a modulated component and a plurality of components of carrier frequency, each carrier frequency component differing in phase from the

others, combining all of said components, and transmitting the resultant wave to a receiving device.

5. The method of modulation which comprises generating a rotating field having an angular velocity determined by waves of carrier frequency, producing by means of said field an alternating current of carrier frequency, and varying the phase of said 10 current in accordance with signals, whereby a wave represented by the equation:

$$-M = A(\cos pt - a \sin pt \cos qt)$$

is generated.

15 6. In a modulating system, a source of modulating waves, a source of carrier waves, a second source of carrier waves differing in phase by 90° from said first carrier waves, means supplied with said carrier waves for 20 producing a rotating magnetic field, means linked by said field and having induced therein a wave of carrier frequency in accordance with the rotation of said field, and means independent of said field for varying 25 the linkage with said means in accordance with signals to cause corresponding variations in the phase of said induced current.

7. A modulation system which comprises, 30 a source of signal waves, a source of polyphase carrier waves, means supplied with said carrier waves for generating a rotating magnetic field, vibratory means linked by said magnetic field, so as to have induced 35 therein a carrier frequency current; the vi-

bration of said means being controlled in accordance with signals, whereby corresponding variations in the linkage are produced to cause variations of phase of the induced current.

40

8. A modulation system which comprises, a source of signal waves, a source of polyphase carrier waves, means supplied with said carrier waves for generating a rotating magnetic field, a plurality of vibratory elements linked by said magnetic field one of said elements being adapted to vibrate in an opposite sense to that of another of said elements, whereby an unmodulated component of carrier frequency induced in said 50 elements is suppressed.

45

9. The modulation system which comprises a source of signal waves, a source of polyphase carrier waves, means supplied with said carrier waves for generating a rotating 55 magnetic field, a plurality of vibratory coils linked with said field, whereby carrier frequency waves are induced therein, and a stationary coil linked by said field and so arranged that the carrier wave induced 60 therein is different in phase from the waves in said vibratory coils, means for vibrating said coils in accordance with signals, and means for combining the resulting waves from at least one of said 65 vibratory coils, with waves from said stationary coil.

In witness whereof, I hereunto subscribed my name this 6th day of July, A. D., 1925.

RALPH V. L. HARTLEY.
